(57) **CLAIM**

The ornamental design for a smart head-mounted camera, as shown and described.

DESCRIPTION

FIG. 1 is a perspective view of a smart head-mounted camera showing our new design, with the camera support omitted for ease of illustration;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the camera support, shown with the camera omitted for ease of illustration;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view of the camera, shown with the camera and the camera support attached;

FIG. 16 is a front view thereof;

FIG. 17 is a rear view thereof;

FIG. 18 is a left side view thereof;

FIG. 19 is a right side view thereof;

FIG. 20 is a top plan view thereof;

FIG. 21 is a bottom plan view thereof;

FIG. 22 is a perspective view thereof in a first use state;

(Continued)

FIG. 23 is a perspective view thereof in a second use state; and, FIG. 24 is a perspective view thereof in a third use state. The broken lines depict portions of the smart head-mounted camera that form no part of the claimed design.
